SWITCH MECHANISM

Albert L. Judson, Minneapolis, Minn., assignor to
 Minneapolis-Honeywell Regulator Company,
 Minneapolis, Minn., a corporation of Delaware

Application January 13, 1938, Serial No. 184,812

9 Claims. (Cl. 200—83)

This invention relates broadly to a switching mechanism and more particularly to a snap acting switch which is operated in response to some condition such as temperature or pressure to open or close a set of contacts. For purposes of illustration only, the device will be described as being responsive to pressure, but it is to be distinctly understood that it may just as easily be made to respond to temperature.

An object of this invention is to provide a switch having reversible contacts so that it will open or close its contacts when the pressure to which it responds reaches a predetermined point, depending upon the position in which they have been placed.

A further object is to provide a pressure responsive switch which may be adapted to break the circuit to an operating device upon the occurrence of a high pressure which indicates a dangerous condition in said device.

A further object of the invention is to provide a high pressure cut-out switch which will automatically return to closed circuit position upon a drop in pressure to a value which is below that which caused switch opening.

Another object is to provide a snap action mechanism operated by a condition responsive device for opening a switch, with additional means also operated by said condition responsive mechanism for positively opening said switch in case said snap acting mechanism should fail for some reason.

A still further object is to provide a high pressure switch which will cut out at a high pressure and cut in again when the pressure drops to a predetermined lower value and which has a means for adjusting this differential.

Another object of this invention is to provide a switch which will cut out at a high pressure and which will attempt to close at a predetermined lower pressure but which has a stop for preventing such return, and a manual means for resetting the switch to closed position after it has once cut out.

Still another object is to provide a switch of the above character which has a single lever which is adapted to act as an adjustment for the differential of the switch or as a manual reset after the switch has opened.

Other objects will become apparent upon a study of the description of the device in connection with the accompanying drawings in which:

Figure 1 is a side elevation of one embodiment of my invention;

Figure 2 is a front elevation of the device

shown in Figure 1 showing the switch operating lever in closed circuit position;

Figure 3 is a side elevation showing the snap action mechanism, being partly in section taken on the line 3—3 of Figure 2;

Figures 4 and 5 are detail views more or less diagrammatic showing two operating positions of the snap action mechanism;

Figure 6 is a perspective view of the main operating lever;

Figure 7 is a perspective view of the bail;

Figure 8 is a section taken on line 8—8 of Figure 2 showing the reversible switch mounting; and

Figure 9 is a perspective view of the reset and differential adjusting lever.

The present device is provided with a base plate 11 to the bottom of which is attached a casing 12 by suitable means such as screws 13 and 14. Within casing 12 is a pressure responsive device such as a bellows (not shown). Depending from the lower portion of casing 12 is a nipple 15 adapted for connection to a source of pressure to be controlled or if the device is intended to respond to temperature changes it may be connected to a thermal bulb by means of capillary tubing.

Mounted on the upper face of base 11 are two upstanding supporting brackets 16 and 17, these brackets are mounted on the base plate by a suitable means such as screws 18 and 19 and are connected near their top by means of a plate

20 having bifurcations 21 and 22 at each end which are inserted in holes 23 and 24 of the brackets. Positioned between these brackets and pivoted thereto as at 25 and 26 is a pair of jaw-

shaped levers 27 having horizontally extending lower portions 28 integrally connected together by cross piece 190. Pivoted to the upper part of this lever at 29 is a U-shaped carriage member 30 having a supporting base portion 31 in which

is seated a main adjusting spring 32. Extending loosely through a hole in connecting plate 20 is a screw 33 having head 34 and a screw threaded stem 35. Securely fastened to said stem and positioned immediately underneath connecting plate 20 is a washer 36 which prevents upward movement of said screw. Threaded on said stem is a nut 37 carrying a horizontally extending portion 38 which coacts with the sides of supporting

brackets 16 and 17 to prevent rotation of the nut upon rotation of the screw. Spring 32 is compressed between the supporting base 31 of the carriage 30 and the non-rotatable nut 37. By

rotating screw 33, nut 37 may be adjusted vertically thereby adjusting the degree of compression.

sion of, and hence the force exerted by spring 32. Secured underneath the base portion 31 of the carriage 30 is a bearing member 39 having a dwell therein in which seats a pin 40 which is connected to the pressure responsive device in casing 12. Spring 32 therefore opposes upward movement of pin 40 by the bellows and adjustment of screw 33 will adjust spring 32 and hence vary the main pressure setting of the device.

10. Each of the lower portions of the jaw-shaped levers 27 has a dwell therein as shown at 41 and 42 in which are seated legs 43 of bail member 45 which legs are in the form of knife edges. As better shown in Figure 7 bail member 45 is provided with lugs 44 which are adapted to fit under the extensions 65, shown in Figure 6, on lower portions 28 of levers 27. This construction will prevent bail 45 from jumping out of the dwells 41 and 42. Hooked through a hole 46 in the top of bail 45 is one end of a spring member 47, the lower end of which is looped over a rod 48 which connects two legs 49 and 50 of a lever 51. This lever is pivoted to the supporting brackets 16 and 17 at 52 and 53 and carries at its upper end two sets of movable switch contacts 54 and 55 which are connected thereto by means of screws 56 and 57. The contact members 54 and 55 are resiliently seated in casings 58 and 59 thus assuring a positive seating when the switches are closed. Supporting brackets 16 and 17 are provided with a pair of ears 60 to which is attached an insulating base 61 by means of screws 62 and 63. The insulating base carries a series of stationary contacts 64 for cooperation with the two pair of movable contacts 54 and 55. It will be noted that the insulated base carries insulating walls 66, 67 and 68 between each of the stationary contacts. Extending inwardly from each of the supporting brackets 16 and 17 are arms 69 and 70 which form a stop for bail member 45 as it is rotated in a clockwise direction. Arm 72 forms a stop for the bail as it is rotated in a counter-clockwise direction which arm and its supporting structure will be described later.

Referring to Figure 3 it will be seen that contact carrying lever 51 is pivoted at 52 and 53, and that spring 47 being tensioned between bail member 45 and rod 48 in lever 51 is tending to rotate the lever in a counter-clockwise direction. When the bail is rotated in a counter-clockwise direction by levers 27 the upper end of the spring 47 will snap to the left which will bring the line of force of the spring on the other side of the pivots 52 and 53. Thus we see in Figure 4 that when this has occurred the force of spring 47 will rotate the lever 51 in a clockwise direction causing the switch contacts to open. The effect of this spring 47 as it passes over center is to open these switch contacts with a snap action. Returning again to Figure 3 it will be seen that spring 47 is tending to rotate bail 45 in a clockwise direction. As the lower end 28 of lever 27 moves to the right it carries with it the lower end of bail 45 and upon continued movement in this direction will cause this lower end to pass beyond the present line of force of spring 47. This will cause the spring to rotate bail 45 in a counter-clockwise direction and take up the position shown in Figure 4, which will occur with a snap action due to spring 47. Thus it will be seen that two distinct snap actions take place, first upon movement to the right of the lower part 28 of levers 27 the bail member 45 will snap 75 in a counter-clockwise direction, which movement

will cause spring 47 to align itself on the opposite side of the pivot pins 52 and 53 of the contact carrying lever causing it to snap in a clockwise direction.

Carried by the lower portion of levers 27 on the side opposite lever 76 is an arm 88 having a bent-in portion 89 for cooperation with casing 58. This is for the purpose of providing a means for positively actuating the switch contacts in case the snap action mechanism should fail. If on a pressure increase the snap action mechanism should fail to operate, portion 89 will engage the casing 58 and positively open the contacts.

As better seen in Figure 3 the stationary contacts 64 are supported by means of brackets 90 mounted on insulation 61 by means of screws 92 screwed in bushings 91 in the insulation 61. Referring to Figure 8 it will be seen that contact member 55 is secured to a block of insulating material 93 by means of pin 94. The block 93 is seated in a cup-shaped member 95 and is resiliently maintained in place by means of spring 96 and screw 57. Thus a good contact is assured on closing movement of the contact carrying lever.

One of the features of this invention is that the position of the contacts may be reversed so that the circuit will be made on an increase in pressure. This is accomplished by removing screws 92 and reversing the position of brackets 90 so that the contacts 64 face in the other direction. It will be seen in Figure 8 that screw 57 may be removed and block 93 and spring 96 reversed in cup 95 and then screwed together again by screw 57. With the contacts so arranged the circuit will be broken when the contact carrying lever is in the position shown in Figure 3, and made when it is in the position shown in Figure 4.

Lever 51 has at the lower portion thereof an extension 73 having a cut-away portion 74. Pivoted at 75 on supporting bracket 17 is a lever 76, shown in detail in Figure 9, having an arm 77 with a horizontally and inwardly extending portion 78 which is adapted to cooperate with the shoulder formed by the cut-away portion 74 of lever 51. A spring 79 has an end 80 which is inserted underneath a portion of supporting bracket 17 and carried about pivot stem 75 for the lever 76 and whose other end 81 is hooked under arm 82 of lever 76 to bias it for rotation in a counter-clockwise direction. The above structure is for the purpose of providing a manual reset for the switch. A V-shaped slot 71a is provided in arm 77 so that if the manual reset feature is not desired arm 77 may be broken off.

Screwed into an ear 83 of the supporting bracket 17 is a screw 84 having a locknut 85. The end of this screw is positioned above arm 82 of the lever 76 to limit the amount of its counter-clockwise rotation produced by the spring 79. It will be noted that this lever 76 has a horizontal arm 86 which has an inwardly extending portion forming the stop 72 for bail 45. Adjustment of screw 84 in and out of ear 83 will therefore adjust the position of stop 72 which, as will be explained later, varies the differential of the device. This feature is used only when the manual reset feature is not desired and arm 77 must be broken off in order to make the differential adjustment feature operative. This is because the engagement of arm 77 with extension 73 will determine the position of the lever 76 unless arm 77 is removed.

Operation

The operation will first be described in connection with the manual reset feature, it being understood that at this time the screw 84 is omitted. Assuming the parts to be in the position shown in Figures 1, 2, and 3, it is noted that the lever 27 has been rotated to its clockwise position and the double snap action mechanism has produced closure of the switch contacts. Lever 10 76 is prevented by a portion of extension 73 from being rotated by spring 79 further in a counter-clockwise direction. This is the condition which prevails when the pressure is at or below the desired value. Upon increase in pressure the pressure responsive device will cause an upward movement of pin 40 which will in turn cause upward movement of carriage member 30 against the action of spring 32 which will produce a counter-clockwise movement of the lever 27 about its pivots 25-28. This in turn will cause its lower end 28 to move to the right snapping the bail 45 in a counter-clockwise direction as explained above which will cause the spring 47 to snap lever 51 in a clockwise direction until legs 49 and 50 strike base member 11. This causes the switch contacts to open. As the lever 51 snaps to its open contact position it raises its extending portion 13 which permits spring 79 to rotate lever 16 in a counter-clockwise direction until arm 77 30 engages the shoulder formed by the cut-away portion 74. Thus on an increase of pressure to the point for which the device has been adjusted by screw 34, the parts will snap over from the position shown in Figures 1, 2, and 3 to that shown in Figure 4. Arm 72 on lever 76 is acting as a stop for the top of ball 45 and is limiting the amount of its counter-clockwise rotation. As set forth above base member 11 is limiting the clockwise rotation of lever 51.

40 The switch contacts are now open and the pressure begins to decrease. Operating pin 40 will be lowered allowing spring 32 to depress carriage 30 and rotate lever 27 in a counter-clockwise direction. This causes the lower end 28 of lever 27 to move generally to the left carrying with it the lower end of the bail which will eventually pass beyond the line of force of spring 47 causing bail 45 to snap to its clockwise position. This will move the line of force of spring 47 on the other side of pivot 52-53 of lever 51 which will cause the lever to rotate in a counter-clockwise direction as shown in Figure 5. It will be noted however that the shoulder formed by the cut-away portion 74 on extension 73 engages portion 78 of arm 77 on lever 76 and thus prevents lever 51 from rotating far enough to close the switch contacts. The only way the switch may now be closed is by manually depressing arm 82 of lever 88 which will remove portion 78 from engagement with the shoulder 74 and permit spring 47 to complete the counter-clockwise rotation of lever 51 and close the switch contacts. The parts have now returned to the position shown in Figures 1, 2, and 3 and the switch is ready to be opened again should the pressure increase to the point for which the device is adjusted.

70 In some instances it may be desired to have a switch which is completely automatic, that is, one which will automatically be returned to closed position after the pressure has returned to a safe value and need not be manually reset. If such a device is desired it is only necessary to eliminate arm 71 of lever 76 with its extending portion 78 by breaking it off at 77a as explained above. If 75 this is done it will be seen that there is nothing

to prevent the complete return of lever 51 to switch closed position by the snap action mechanism. In a device of this type it may be desirable to have an adjustable differential for the snap action mechanism so that the pressure at which the switch will close may be adjusted. This adjustment is accomplished by means of screw 84.

Assume for example that the device is adjusted so that the switch contacts are snapped open 10 at a pressure of 180 pounds. The parts will now be in the position shown in Figure 4 with the bail 45 resting against the stop arm 72 of lever 76. As the switch contacts are open at this time the pressure will begin to drop which will cause the 15 lower end 28 of lever 27 to move generally to the left. At a pressure of say 160 pounds the lower end of the bail will have moved beyond the line of force of spring 47 and the switch will snap shut, it being remembered that arms 77 and 78 20 have been removed from lever 76 so that nothing prevents the complete operation of lever 51 by the snap action mechanism.

The lower the arm 72 is positioned the greater the angle between the bail 45 and the spring 47 25 as viewed in Figure 4 and hence the greater the effect of the force exerted by spring 47 tending to rotate the bail in a counter-clockwise direction. This means that the pressure in the bellows must drop lower, say to 140 pounds, to permit the main 30 spring 32 to develop a force strong enough to swing levers 27 to the left and cause bail 45 to snap over center.

As set forth above the position of arm 72 is determined by screw 84 which therefore determines 35 the differential of the device. The lower the arm 72 is positioned the greater will be the operating differential.

If it is desired to produce a switch which will close on high pressure it is necessary only to reverse the position of both the stationary and movable switch contacts as described above. In this case the manual reset will act to maintain the switch closed until manually opened. The differential adjustment will work the same except 45 that it will determine the pressure at which the switch breaks instead of the pressure at which it makes.

It might occur sometimes that the snap action mechanism would fail for some reason such as 50 the breakage of spring 47. In such a case it might be dangerous if the switch was not opened upon the occurrence of a high pressure. For this reason I have provided the arm 89 on lever 27 which if the snap action mechanism should fail 55 to work would strike the contact carrier 58 and positively move the switch to open position.

Many changes and modifications of this invention will occur to those who are skilled in the art and therefore it is to be distinctly understood 60 that I am not to be limited by the illustration and description of this particular embodiment but rather by the scope of the appended claims.

The present switching device is of the same general type as the one disclosed by Carl G. 65 Kronmiller in application Serial No. 184,811 filed concurrently herewith.

The expression "double snap action mechanism" as used in the claims is intended to cover any mechanism wherein one element snaps and 70 either directly or indirectly causes a second element to snap.

I claim as my invention:

1. In a control device of the character described, a control member, a condition responsive 75

device, a spring, means operated by said condition responsive device against the action of said spring, said means operating a double snap action mechanism comprising a bail having two stops and coacting at one end with said means and being connected at the other end with one end of an over-center spring, said spring being connected at its other end to said control member, a lever pivoted intermediate its ends to a stationary support, a spring tending to rotate said lever in one direction, stop means cooperating with one arm of said lever to limit such rotation, the other arm forming one of the stops for said bail, and means for adjusting the position of said lever and hence the differential of the snap action mechanism.

2. In a control device of the character described, a control member, a condition responsive device, a spring, means operated by said condition responsive device against the action of said spring, said means operating a double snap acting mechanism comprising a bail having two stops and coacting at one end with said means and being connected at the other with one end of an over-center spring, said spring being connected at its other end to said control member, a lever pivoted intermediate its ends to a stationary support, one arm of said lever forming one of the stops for said bail, an adjustable screw, and a spring holding the other end of said lever against said adjustable screw, adjustment of said screw adjusting the differential of said snap acting mechanism.

3. In a control device of the character described, a control member, a condition responsive device, a spring, a lever operated by said condition responsive device against the action of said spring, said lever operating a double snap acting mechanism comprising a bail having two stops and coacting at one end with said lever and being connected at the other with one end of an over-center spring, said spring being connected at its other end to said control member, a second lever pivoted intermediate its ends to a stationary support, a spring tending to rotate said lever in one direction, stop means cooperating with one of said levers to limit such rotation, the other arm forming one of the stops for said bail, and means for adjusting the position of said lever and hence the differential of the snap action mechanism and means for adjusting said first mentioned spring to adjust the main setting of the control device.

4. In a control device of the character described, a double snap action mechanism including a bail having two stops, a condition responsive device for operating said snap action mechanism in one direction, a spring for operating said snap action mechanism in the other direction, a pivoted control lever actuated by said snap action mechanism, a second pivoted lever having an arm, a projection on said control lever adapted to engage said arm to prevent actuation by said snap action mechanism under the influence of said spring, means for manually moving said arm to permit operation of said control lever by said snap action mechanism, means for breaking off said arm if it is not desired, a member on said lever forming one of the stops for said bail, and an adjustable means for positioning said stop member in order to adjust the differential of the device when said arm has been broken off.

5. In a control device of the character described, a snap action mechanism, a condition responsive device for operating said snap action

mechanism, a pivoted control lever actuated by said snap action mechanism, a second pivoted lever having three arms, one arm acting as a stop for preventing operation of said control lever in one direction by said snap action mechanism, a second arm providing a manual means for removing the stop for permitting such operation, means for removing said first arm when it is not desired, a third arm cooperating with said snap action mechanism to determine the differential of operation thereof, and means for adjusting said third arm, said means being operable only after said first arm has been removed.

6. In a pressure responsive switch, a double snap action mechanism including a bail having two stops, a condition responsive device for operating said snap action mechanism in one direction, a spring for operating said snap action mechanism in the other direction, a pivoted control lever carrying a movable contact, means for operating said control lever by said snap action mechanism, a stationary contact positioned for cooperation with said movable contact, a second pivoted lever having three arms, the first arm cooperating with said control lever to prevent its operation by said snap action mechanism under the influence of said spring, the second arm acting as a manual means for moving said first arm to permit such operation, means for removing said first arm from said lever if it is not desired, the third arm forming one of the stops for the bail and hence determining the operating differential of the snap action mechanism, and means for adjusting the position of said third arm, said last named means being inoperative except when said first arm has been removed.

7. In a pressure responsive switch, a double snap action mechanism including a movable contact carrying lever and a bail having two stops, a condition responsive device for operating said snap action mechanism in one direction, a spring for operating said snap action mechanism in the other direction, a movable contact carried by said lever, a stationary contact positioned for cooperation with said movable contact, a second pivoted lever having three arms, means constantly tending to rotate said lever, the first arm cooperating with a portion of said contact carrying lever to prevent its operation in one direction, the second arm providing manual means for moving said first arm to permit such operation, said first arm having a notch cut therein so that it may be broken off if it is not desired, the third arm forming one of the stops for the bail, a fixed element having a screw threaded hole therethrough located above said second arm, and a screw adapted to be threaded through said hole to limit the rotation of said second lever as produced by said spring when said first arm has been broken off, to adjustably position said third arm.

8. An electric switch comprising in combination, a lever, a first contact, means for resiliently mounting said contact on said lever including a piece of insulating material, said contact being mounted therein, a spring located adjacent said insulation, retaining means for maintaining the parts in assembled relation, said insulation and spring being reversible with respect to said lever and retaining means, a second contact mounted at one side of said first contact on a stationary support, and means for mounting said second contact on the opposite side of said first contact.

9. In a device of the character described comprising in combination, a double snap action

mechanism including a bail, a pivoted control member, a tension spring connecting one end of said bail to said control member, condition responsive means for moving the other end of said bail on variations in said condition, a spring pressed stop member positioned to cooperate with said control member in such a manner that on a variation in said condition in one direction said condition responsive means will move said bail 10 which will in turn snap said control member from a first position to a second position, and on a

variation in said condition in the opposite direction said condition responsive means will move said bail to snap said control member from said second position into engagement with said stop member, manual means for moving said stop member whereby said control member is snapped into said first position, and a pair of stops for limiting the movement of said one end of said bail, one of said pair of stops being carried by said manually movable stop member. 10

ALBERT L. JUDSON.
